UNITED STATES PATENT OFFICE.

CHARLES R. NEILL AND EDWARD T. GATRELL, OF TULSA, OKLAHOMA.

ROOF CONSTRUCTION.

1,316,968.

Specification of Letters Patent. Patented Sept. 23, 1919.

Application filed May 16, 1918. Serial No. 235,001.

To all whom it may concern:

Be it known that we, CHARLES R. NEILL and EDWARD T. GATRELL, citizens of the United States, and residents of Tulsa, in 5 the county of Tulsa and State of Oklahoma, have invented certain new and useful Improvements in Roof Constructions, of which the following is a specification.

This invention relates to roof constructions and it comprises a roof for a tank or the like made of sections of metal crimped and hooked along their edges and soldered to each other, the roof being placed upon the tank or other structure with a loose connection therebetween, said roof being sealed to the side of the tank by an expandable member or expansion joint, the expansion joint comprising a continuous strip of lead or its equivalent and being secured to the 20 upper edge of the tank; all as more fully hereinafter set forth and as claimed.

In constructing a tank to hold oils and other liquids, it is desirable to provide a leak-proof connection or sealing member between the tank and its roof and it is also necessary to provide for the expansion and contraction of the metal due to changes in temperature. In prior constructions of this character attempts have been made to construct a tank which is leak-proof, but in such constructions no allowance was made for the expansion and contraction of the parts. In any construction where the edge of a tank roof is secured directly to the tank or is indirectly secured to the tank through the use of some rigid element, the desired result is not obtained. In very hot weather the roof expands to such a degree that it is apt to open a seam and in colder weather it may 40 contract to such an extent as to break the connection between the roof and the tank. In some constructions provision has been made for expansion and contraction but without securing a leak-proof or hermetically sealing connection.

In the present invention we provide a tank with a roof secured to the tank through the medium of a flexible expansion joint which permits expansion and contraction of 50 the various elements, and at the same time, we provide a construction which is entirely leak-proof. When used on an oil tank, this construction prevents the escape of gases and vapors and prevents inflow of air into 55 the tank.

In the present construction a continuous

expansion strip of lead is secured to the edge of the roof, and the shell of the tank is provided with an angle iron at its upper edge, the expansion strip embracing the 60 angle iron and being secured to the shell of the tank.

In the accompanying drawings we have shown several advantageous embodiments of this invention. In this showing— 65

Fig. 1 is a partial plan view of a roof constructed in accordance with our invention;

Fig. 2 is a vertical section taken on the line 2—2 of Fig. 1 showing the expansion 70 strip made of lead; and

Fig. 3 is a similar view showing an expansion strip made of corrugated tin.

In the accompanying drawings letter A designates the tank as a whole. It is provided with a roof B. The roof as shown consists of a plurality of sections 1 which are crimped along their edges and hooked to each other. Solder may be employed to insure perfect joint between the sections. The 80 tank is provided with the usual rafters 2 for supporting the roof and a sheathing of wooden strips 3 which rests upon the rafters and forms a foundation for the roof. Angle iron 4 is secured to the shell of the tank at 85 its upper edge. The roof is not connected rigidly to the shell of the tank or to the angle iron carried at the top of the tank, but is provided with an expansion strip 5 by means of which a flexible connection is 90 made. In Fig. 2 the expansion strip is shown made of sheet lead and in Fig. 3 the expansion strip 5' is made of corrugated 95 tin. Other suitable matter, such as fabric water-proofed with flexible oil-proof material such as chromated glue, viscose cellulose, etc., may be employed for this purpose. The expansion strip is soldered to the edge of the roof at 6 and extends over the outer edge of the angle iron, embracing 100 the angle iron and is secured to the shell of the tank between the tank and the vertical leg of the angle iron by bolt 7. Rivets or bolts may be employed for this purpose, and the expansion strip may be calked on top 105 between the angle iron and the shell.

When a roof of this character has been assembled, the connection between the tank and the roof is leak-proof, and if the tank contains volatile liquids the escape of vapors 110 and gases is prevented. Any inflow of air is also prevented. As the roof is not rigidly

- connected to the shell of the tank and as the flexible expansion strip will permit the roof to move relatively to the edge of the tank, provision is made for expansion and contraction of the parts due to changes in temperature and the tank may be used in any climate, even where it will be subjected to marked changes in temperature. When the expansion strip is made of lead or other metal, an excellent lightning arrester is provided. If a bolt of lightning should hit the roof of the tank, it would pass through the metal expansion strip and down the metal side of the tank to the ground.
- 10 5
- 15 What we claim is:—
1. A roof for storage tanks and the like comprising a metal covering for the tank, an angle iron secured to the edge of the tank at the top thereof, with a loose connection between said metal covering and said angle iron, an expansion strip of flexible metal secured to the edge of the roof, said expansion strip embracing said angle iron and being secured to the shell of the tank.
  2. A roof for storage tanks and the like comprising a metal covering for the tank, with a loose connection between said metal
- covering and said tank, an expansion strip of flexible metal secured to the metal covering, and to the tank, said strip forming a leak-proof connection between the tank and the roof, and permitting expansion and contraction of the same.
3. A roof for storage tanks and the like comprising a metal covering for the tank, an angle iron secured to the edge of the tank at the top thereof, with a loose connection between said metal covering and said angle iron, an expansion strip of lead secured to the edge of the roof, said expansion strip embracing said angle iron and being secured to the shell of the tank.
4. A roof for storage tanks and the like comprising a metal covering for the tank, with a loose connection between said metal covering and said tank an expansion strip of lead secured to the metal covering, and to the tank, said strip forming a leak-proof connection between the tank and the roof, and permitting expansion and contraction of the same.

In testimony whereof, we affix our signatures hereto.

CHARLES R. NEILL.
EDWARD T. GATRELL.
